UNITED STATES PATENT OFFICE.

FRANK PARDEE, OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA.

SPIRAL SEPARATOR.

Original application filed February 21, 1925, Serial No. 10,740. Divided and this application filed April 17, 1925. Serial No. 23,776.

In an application Serial No. 10,740 filed February 21, 1925, I have disclosed and claimed broadly a spiral structure and method of manufacturing the same. The chute 5 described in said former application with certain modifications can be used as a separator as well as a lowering chute such as specifically shown and claimed. The present application is a division of my above 10 identified co-pending case.

My improved separator is preferably made of a fairly heavy gauge pipe which is bent to spiral form of the required pitch and diameter. This form of apparatus provides 15 an extremely rigid structure which is practically self-supporting. This does away with the necessity of providing either the central supporting post used in most former types and in many cases the runway may 20 be supported or held in place merely by suitable brackets or tie bars anchored to adjustable columns in the building or to other convenient supports such as walls or flooring and roof beams.

25 Embodiments of the invention are illustrated in the accompanying drawings in which—

Fig. 1 is a side elevation showing a self-supporting runway;

30 Fig. 2 is a view of an alternative construction;

Fig. 3 is a detail showing a portion of the pipe used for making the runway illustrated in Fig. 2;

35 Fig. 4 is a detail of a portion of a modified form of separator;

Fig. 5 is a detail section on line 5—5 of Fig. 4.

40 Referring in detail first to Fig. 1 of the drawings, the separator here shown consists of a runway formed of a pipe-like member 10 which is bent to the pitch and diameter best suited for handling the materials to be separated. The embodiment illustrated is 45 adapted for separating coal from slate. The mixed materials are fed by gravity through a chute 12 to the mouth 14 at the upper end of the tubular runway. As the materials travel downwardly in their spiral path a 50 separation takes place due partly to centrifugal action and the different frictional characteristics of the two classes of material. The coal being hard and bright or of cubical

fracture tends to travel at a faster rate and centrifugal force aids in compelling it to 55 follow in an outer path. The slate on the other hand is of flatter fracture and is of rougher texture, thereby presents greater friction and it tends to travel along an inner path. It is thus apparent that as the mass 60 reaches the lower end or cut-away portion indicated at 16, the coal will climb upwardly and over the edge 18 in the direction of the arrows 20 and the slate will fall over the edge 22 which is preferably at a lower 65 elevation than the edge 18. A suitable ridge plate formed of inclined members 24 and 26 tends to deflect the coal in the direction of the arrows 20 and the slate in the direction of the arrows 28. Suitable chutes not 70 shown may be provided to convey the material to storage bins as will be understood. The ridge plates 24 and 26 may serve as a support for the lower end of the separator runway 10 and brackets or tie-bars 30 may 75 be secured by bolts 32 to the runway and by bolts 34 to existing structure members in the building in which the separator is located. It is apparent that the pipe-like runway is of sufficient rigidity to be self-supporting and provides an extremely simple, 80 yet efficient, separator.

Instead of forming the runway of one continuous spiral pipe section as shown, it 85 may be made up of two or more sections united by any suitable form of joint such as flanged rings or the like.

The chute 36 is provided for catching the intermediate class of material which fails to climb over the edge 18 or 22. 90

The pipe-like separator above described differs from those heretofore used in that the runway is a closed structure. This prevents the escape of dust into the surrounding atmosphere and, of course, prevents 95 pieces travelling at a fast rate from flying off or leaving the runway.

In Fig. 2, I have illustrated a slightly modified construction in which the runway 38 is of arcuate form in cross-section. This 100 type of runway is conveniently made by the method disclosed in my former application above referred to. To make this runway, I bend a length of pipe into spiral form of the required pitch and diameter and cut 105 away a central portion along the lines σ

and p . This will leave a piece such as shown in Fig. 3. I then sever this piece along the spiral line indicated at t . This forms two spiral sections one of which is inverted and joined to the end of the other by means of a splice plate 40 indicated in Fig. 2. In this form of device, the runway is supported by uprights 42 and brackets 44 as shown.

10 In Fig. 4, I have shown a further modification in which the runway 50 is formed of a spiral pipe having openings 52 formed therein, these openings being separated by connecting members 54. This forms a very 15 rigid type of runway which is practically self-supporting it merely being necessary to provide tie-bars 56 which can be fastened to any fixed part of the building in which the apparatus is located so as to anchor the 20 separator in place. This form of runway is adapted to be inverted when one portion becomes badly worn. This will be apparent from examination of Fig. 5 in which it will be noted that the edges 56 and 58 are equi- 25 distant from the horizontal center line $u-v$ passing through the center of the arc representing the cross-sectional contour of the runway. As thus proportioned when the 30 bottom of the runway becomes badly worn 35 the entire separator can be inverted and the part which was formerly the top then becomes the bottom. This practically doubles the life of the separator.

In the form shown in Figs. 2 and 4, the 35 runway will be cut away as indicated to form lips over which the different classes of material will be discharged when they reach the lower end of the runway. These lips indicated at 18 a and 22 a are substantially the 40 same as indicated in Fig. 1 and chutes similar to those illustrated in said figure will be provided for guiding the separated materials to suitable storage bins. In the form illustrated in Fig. 4 which is adapted to be 45 inverted for reuse when one side becomes badly worn, it is, of course, apparent that the part which becomes the lower end will have to be cut away to form proper discharge lips. This work can be done prior 50 to the erection of the spiral in its inverted position and the work can conveniently be done by the same crew of workmen who make the change.

While I have described with great par- 55 ticularity the specific embodiments of the

invention herein shown, it is not to be construed that I am limited thereto as changes in arrangement and substitution of equivalents may be made by those skilled in the art without departing from the invention as defined in the appended claims.

What I claim is:—

1. A separator comprising a tubular runway of spiral form adapted to receive mixed materials at its upper end, the lower end of 65 said tubular runway being cut away to form discharge lips at such an elevation that different classes of material will climb laterally over the edges of said lips.

2. A separator comprising a spiral runway of concave cross-section and having a cut away portion at the lower end thereof, one edge of which is spaced at a predetermined elevation above the low point of the concave runway so that the material travelling thereon can climb over said edge. 70

3. A separator comprising a spiral runway of concave cross-section and having an outer edge higher than an inner edge so that one class of material will climb over the 80 high edge and another will be discharged over the low edge.

4. A separator comprising a tubular runway of spiral form adapted to receive mixed materials at its upper end, the lower end of 85 said tubular runway being cut away to form discharge lips at such an elevation that different classes of material will climb laterally over the edges of said lips and means for deflecting the separated materials in 90 different directions.

5. A separator comprising a tubular runway of spiral form adapted to receive mixed materials at its upper end, the lower end of 95 said tubular runway being cut away to form discharge lips at such an elevation that different classes of material will climb laterally over the edges of said lips, inclined members for deflecting the materials which climb over said lips and a chute for carrying off the remainder. 100

6. A separator comprising a spiral runway of substantially C-shape in cross-section having integral side and bottom walls, said runway being adapted to be inverted for 105 reuse when badly worn.

In witness whereof, I have hereunto signed my name.

FRANK PARDEE.
